DISPENSING AND ATOMIZING CONTAINER

Leo D. Reimann, Salem, Oreg.

Application June 1, 1949, Serial No. 96,543

2 Claims. (Cl. 299—90)

1

This invention relates generally to containers and particularly to a dispensing and atomizing container.

The main object of this invention is to provide a dispensing container which is adaptable to a wide variety of uses including liquids and free flowing powder material and it can be used with an atomizer effect.

The second object is to construct a dispensing container of the collapsing type which can be completely sealed to prevent loss or evaporation of contents and which has a removable elongated neck which may be stored within the container.

The third object is to construct a dispensing container of the class described with a filler plug at one end and with a cap covering the filler plug, in which the cap is used as a means for rotating the plug.

I accomplish these and other objects in the manner set forth in the following specification as illustrated by the accompanying drawings, in which:

Fig. 1 is a plan of the container with the cap removed.

Fig. 2 is a vertical section through the container.

Fig. 3 is an enlarged section taken along the line 3—3 in Fig. 1.

Like numbers of reference refer to the same or similar parts throughout the several views.

Referring in detail to the drawing, there is shown a container 10 of flexible or semi-flexible material, such as rubber, polyethylene, nylon or vinyl in any of its forms. The neck 11 is integral with the container 10 and has formed therein a threaded filler opening 12 for a plug 13, having a screw slot 14, by means of which the plug 13 can be turned.

The neck 11 has formed therein an opening 15 which communicates with the tube 16 whose lower end 17 extends almost to the bottom 18 which is secured in place at the lower end of the container 10 in any convenient manner. It is through the tube 16 that liquids 19 are forced upwardly through the opening 15 when the walls of the container are partially collapsed by manual pressure.

In the neck 11 is also formed an air duct 20 which intersects the opening 15 in order to produce an atomizing effect. A thin lip 21 overhangs the opening 15 and becomes a seal therefor

2

when the cap 22 is placed on the neck 11 and secured by means of the threads 23. In this form of the device I have provided a superior form of atomizer in which the liquid 19 is brought up to the point of atomization by manual pressure on the container 10 and atomized by air placed under pressure by the same action.

When not in use, the cap 22 effectively seals the container by forcing the lip 21 to seal the opening 15.

I claim:

1. A container of resilient material having a filler cap threaded into the top end thereof, a tube extending downwardly through the top of said container to a point near the bottom thereof, said tube communicating with the exterior of the container, an air duct in the top of said container intersecting the outlet of said tube, a lip formed above said outlet and air duct, and a cap threaded on the top of said container adapted to bear upon said lip and close said outlet.

2. A container of resilient material having partially collapsible sides and having a neck forming a top therefor, said neck having a threaded filler cap therein, said neck also having a tube extending downwardly toward the bottom of the container and opening outwardly through the top thereof, an air duct in said neck intersecting the outlet of said tube, said air duct having a thin

30 lip extending beyond the end of said neck across the outlet of said tube, a cap for said duct adapted to engage said lip for closing said outlet when said cap is tightened upon said neck.

LEO D. REIMANN.
